(57) **CLAIM**

The ornamental design for a device for wireless measuring pressure of tyres, as shown.

DESCRIPTION

FIG. 1 is a front perspective view of the device for wireless measuring pressure of tyres, showing our new design, illustrated by means of drawings;

FIG. 2 is a rear perspective view thereof;

FIG. 3 is a front view thereof;

FIG. 4 is a rear view thereof;

FIG. 5 is a left side view thereof;

FIG. 6 is a top view thereof; and,

FIG. 7 is a bottom view thereof.
